UNITED STATES PATENT OFFICE

GEORGE E. CROSLEY, OF MILTON, WISCONSIN, ASSIGNOR TO THE BURDICK CORPORATION, OF MILTON, WISCONSIN, A CORPORATION OF DELAWARE

THERAPEUTIC APPLIANCE

Application filed January 18, 1929. Serial No. 333,342.

My invention relates to therapeutic appliances.

It will be described with particular reference to an appliance especially adapted for applying red and infra-red rays locally to affected parts of the body.

It has been found that red and infra-red rays penetrate human living tissue and are there converted into heat with salutary effect upon various diseased conditions. But, heretofore, it has been possible to apply such rays to the body only with accompanying difficulties and limitations that have, under some conditions, proved to be seriously detrimental factors.

One of the difficulties heretofore encountered in the use of red and infra-red rays is the fact that the generators also produce a considerable amount of heat which reaches the parts to be treated by conduction and convection and is absorbed by and affects the skin and outer layers of tissue. Furthermore, the appliances have been of a relatively general or extensive area application type rather than of a type permitting localization of the application of the rays to substantially the diseased region. In consequence, in order to obviate objectionable discomfort to the patient, it has been necessary to limit the amount of red and infra-red energy applied and to remove the source to such distances from the patient that the effectiveness of the treatment is greatly curtailed. In other words, the feasible and usable intensity of the desired red and infra-red energy has been largely dependent upon and lessened by the unavoidable presence of phenomena productive of discomfort or other objectionable conditions that have governed or at least substantially influenced the intensity of the desirable application. Furthermore, it has been practically impossible to apply red and infra-red rays directly and only locally to relatively small areas, such as is often desirable in mouth, throat, nose and other body cavity work. And with appliances heretofore available it has been practically impossible accurately and repeatedly to control and vary the intensity of the application.

One of the objects of this invention is to

provide an improved appliance for applying red and infra-red rays.

A further object is to provide an appliance for concentrating or localizing the application of red and infra-red rays. 55

Another object is to provide an appliance particularly adapted for applying such rays to localized areas not readily accessible, such as body cavities.

Another object is to provide an appliance wherein the patient is subject only to the desired red and infra-red rays, convective and conductive heat being substantially eliminated. 60

A further object is to provide an infra-red ray appliance in which the intensity of the rays may be accurately regulated. 65

Other objects and advantages will herein-after appear.

In accordance with the general features of the invention, a ray generating element or generator is provided, which, when heated, will emit a large proportion of red and infra-red energy. These rays are conducted to the desired area by an applicator that localizes their application and whose relation to the generating element may be accurately and closely regulated to control their intensity. Substantially all of the undesirable rays are absorbed so that they do not reach the patient. 70 75 80

In the drawings:

Fig. 1 is a longitudinal section of an appliance embodying the invention;

Fig. 2 is a cross-section taken on the line 2-2 of Fig. 1; 85

Fig. 3 is a cross-section taken on the line 3-3 of Fig. 1;

Fig. 4 is a cross-section taken on the line 4-4 of Fig. 1;

Fig. 5 is a cross-section taken on the line 5-5 of Fig. 1; 90

Fig. 6 is a plan view of the appliance; and

Fig. 7 is a cross-section taken on the line 7-7 of Fig. 3. 95

The appliance chosen for illustration comprises, in general, a ray generating element 11, enclosed in a casing or housing having an inner wall 12 and an outer wall 14 that are spaced apart to provide a chamber for the circulation of a suitable cooling medium, 100

such as water. The housing adjustably supports an applicator 21 for directing, confining and conducting the rays from the generating element to and upon a localized area 5 of or within the body of a patient.

The generating element may be constructed in various ways. As shown, it comprises a resistor wire 11' helically wound and embedded in a block of fused quartz having a 10 flat front side facing the applicator. The wire for forming the resistor coil may be composed of tungsten, platinum, nichrome or other suitable materials, such that when an electric current flows therethrough it will 15 glow to the desired degree of color and brightness. Embedding materials other than quartz may be used, such as carborundum and the like.

A lug 10 is formed on the upper side of 20 outer wall 14 by which the appliance may be suspended on a hook 9 depending from any suitable support. The rear of the inner casing is closed by a removable cap 13 which, particularly if the embedding material of the 25 generator is transparent, may be curved and polished to form a reflector. A removable cap 15 serves to close the rear end of the outer casing. By thus closing the inner and outer casings by aligned removable caps access to 30 the cooling-fluid chamber or to the central generator chamber may be readily had.

A cylindrically shaped applicator support 16 extends forwardly from the housing and slidably carries an applicator holder 17. Holder 17 is provided at each end with an 35 annular groove having a material such as felt or rubber therein to engage and hold an applicator rod 21, preferably of quartz. Other materials, such as glass or rock salt, 40 may be used as applicator rods if desired and conditions permit.

One end of rod 21 extends into the generator chamber into close proximity to generating element 11. This end of the rod, being 45 always quite close to the ray generator, has a tendency to become heated even though the temperature of the generating chamber is kept at a low value by the surrounding cooling chamber. In order to increase the cooling 50 rate of this end of the rod, a collar 8, of a material having a high heat conductivity such as copper is placed around the rod in such proximity as to provide just sufficient clearance for the rod to slide therethrough. 55 The outer periphery of the collar is in engagement with the inner wall of the cooling chamber so that a path of high heat conductivity is afforded between the inner end of the applicator and the cooling medium.

60 On its lower side holder 17 is provided with a rack 22 while an arm 23 extending downwardly from support 16 carries a worm wheel 24, the teeth of which mesh with the teeth of rack 22. By manually rotating the 65 worm wheel, the distance between the rear

end or base of the quartz applicator rod and the generating element may be varied.

In certain kinds of treatments it may be desirable to screen out certain wave lengths of rays generated by the ray generator. Thus 70 it may be desirable in one case to treat a patient with infra-red rays of a long wave length and in another case to treat the patient with a ray of a shorter wave length. In order to accomplish this result a channel 75 39 is provided leading through walls 12 and 14 of the generating and cooling chambers through which a screen 40 may be inserted to extend between the applicator and the ray generator. The character of material used in the screen will, of course, depend upon the type of ray to be screened out. In a large majority of cases the appliance will be used without a screen, since the rays generated by the generator described may be used with highly satisfactory results in most cases without screening.

80 An indicator 26' may be attached to the upper forward end of holder 17 and provided with an arrow or other suitable mark thereon to register with a scale upon the tubular support. Thus the separation of the base of the applicator rod and generating element may be calibrated so that their relationship may be determined and any desired condition repeated as desired. In order that the operator may know the temperature at the remote or emitting end of the applicator rod, a thermocouple 20 may be embedded 85 therein and connected to a suitable indicating means shown diagrammatically in Fig. 6.

90 The housing has a suitable grip 26 to facilitate its being held and manipulated. Grip 26 has a cylindrical aperture therein communicating with the generating chamber and provided with a shoulder 28 against which a supporting block 29 for the generating element may rest. The supporting block is held in position by a pair of rigid conductors 31 which lead to a plug 32 and make electrical connection with any suitable source of electrical current through a cord 33. Plug 32 is provided with a washer 34 retained thereon by a screw 35 extending into the plug. Washer 34 engages an annular groove within the grip and serves to retain the plug therein. The generating element, supporting block and plug may be removed from the appliance as a unit by removing the lower cap 30 of the grip.

105 110 115 120 125 130 The grip is provided with a pair of passages 36 which communicate with the cooling-fluid chamber. One of these passages is provided with a tube 37 that extends into a remote position in the chamber so that a cooling medium such as water conducted into the chamber through the tube will traverse the entire cooling chamber before reaching the other passage from which the water is conducted from the appliance.

Each of the passages is provided at the lower end of the grip with a flexible hose 38 one of which may be attached to a suitable source of water supply, such as a faucet, 5 while the other hose leads to any suitable place for discharging the water.

The operation of the appliance is as follows: When the operator wishes to treat a patient with infra-red rays, an electric current 10 is conducted through the generating element by operating any suitable switch, not shown, and the water is caused to circulate through the cooling-fluid chamber surrounding the generator chamber. The intensity of 15 the rays may be regulated as required by rotating the worm wheel 24 to vary the gap between the generator and the base of the applicator rod.

By noting the position of indicator 26' on 20 the scale, any desired intensity may be obtained. The heat produced by the generating element during the generation of the rays is carried from the generator chamber by the cooling medium circulating in the surrounding 25 cooling-fluid chamber and the red and infra-red rays from the generating element will be transmitted along the quartz rod. The energy directed rearwardly from the generating element will strike the concave 30 polished surface of cap 13 and, after reflection, will also pass along the quartz rod. The quartz rod transmits the red and infra-red rays with practically no absorption so that the rod will not become heated thereby, 35 permitting practically all of the generated red and infra-red rays to be applied by contacting the rounded end of the quartz rod with the parts to be treated.

However, because the loss of energy to the 40 applicator rod is very materially influenced by the length of the air gap between the generator and the base of the rod, the intensity of the rays conducted by the applicator may be regulated between quite wide limits.

In the event it is unnecessary to afford such 45 effective cooling as would be obtained from the use of a circulating cooling medium such as water,—for example, if a lamp is intended for treatments of only relatively short duration, the cooling chamber may be filled with a poor heat conducting material such as asbestos to prevent the appliance from getting hot on the outside. The appliance then operates satisfactorily for such periods in which 50 the possibility of overheating is absent.

Having thus described the nature and an embodiment of my invention, what I claim and desire to secure by United States Letters Patent is as follows:

1. A therapeutic appliance comprising, 55 an element for generating red and infra-red rays, a chamber for housing the element, a conductor in the form of a quartz rod extending into the housing, a holder for the quartz rod carried by the housing, and means for

adjusting the conductor so that the distance between the element and the end of the conductor proximal to the element may be varied, thus regulating the intensity of radiation available at the distal end of the conductor. 70

2. A therapeutic appliance comprising, an element for generating red and infra-red rays, a chamber for housing the element, a quartz rod extending into the chamber, a support carried by the chamber, a holder for the quartz rod slidably mounted in the support for varying the distance of the rod from the element and the intensity of heating of the latter, and means for moving the holder in the support. 75

3. A therapeutic appliance comprising, an element for generating red and infra-red rays, means for conducting the rays from the element, and means for varying the position of the conducting means with respect to the element to control the intensity of the rays. 80

4. A therapeutic appliance comprising, an element for generating red and infro-red rays, a mounting for said element, a conducting rod for conducting the red and infra-red rays from said element, and means for adjusting the position of said rod to control the intensity of the rays conducted from the element. 90

5. A therapeutic appliance comprising, a grip having a plurality of passages therein, a generating chamber supported by the grip, an element in said chamber for generating red and infra-red rays, electrical conducting means leading through a passage in the grip and attached to the element for heating the element, a cooling chamber substantially surrounding the generating chamber, a tube extending into the cooling chamber adapted to conduct a cooling medium into the chamber, the cooling medium leaving the chamber through a passage in the grip, and a rod extending into the generating chamber in liquid tight connection therewith to conduct the red and infra-red rays therefrom. 100

6. A therapeutic appliance comprising, a grip having a plurality of passages therein, a generating chamber supported by the grip, an element of said chamber for generating red and infra-red rays, a cooling chamber substantially surrounding the generating chamber, a tube extending into the cooling chamber adapted to conduct a cooling medium into the chamber, the cooling medium being conducted from the chamber through a passage in the grip, a rod extending into the generating chamber to conduct the rays therefrom, a support for the rod integral with said chambers and means for moving the rod longitudinally in the support to regulate the intensity of the rays. 110

7. A therapeutic appliance comprising a red and infra-red ray generator, a rod ex- 125

130

tending into close proximity to the generator to conduct the rays therefrom, and an annular conducting member surrounding the end of the rod proximal to the generating element to dissipate the conducting heat in the portion of the rod proximal to the generating element.

8. A therapeutic appliance comprising, an element for generating red and infra-red rays, a chamber for housing the element, a quartz rod extending into the housing, a holder for the quartz rod carried by the housing, and means for moving the holder to shift the quartz rod toward and from the generating element and thereby varying the intensity of the red and infra-red rays emitted by the apparatus.

9. A hand operable therapeutic appliance comprising a body portion, a downwardly extending handle portion, an element for generating light rays mounted in said body portion, electric conductors connected thereto and extending outward through said handle portion, a quartz rod extending into said body portion, a holder for the quartz rod carried by said housing, means for moving the holder to shift the quartz rod, and visible indicia on the body portion for indicating the position of the quartz rod.

36 10. A hand operable therapeutic appliance comprising a body portion having an auxil-

iary housing therein, a downwardly extending handle portion, an element for generating light rays mounted in said auxiliary housing, electric conductors connected thereto and extending outward through said handle portion, a quartz rod extending into said auxiliary housing, a holder for said quartz rod carried by said housing, a rack and pinion mechanism for moving the holder of the quartz rod, and cooperating means between said housing and said holder to visibly indicate the position of said quartz rod.

11. A hand operable therapeutic appliance comprising a housing member, a handle on said housing, an element for generating light rays mounted in said housing, electric conductors connected thereto and extending outward through said handle, a quartz rod extending into said housing, a heat conducting ring positioned in said housing around the end of said quartz rod, an insulating holder for said quartz rod carried by said housing, and means on said housing cooperating with means on said holder for manually shifting the position of said quartz rod outwardly or inwardly from said ray generating element.

In witness whereof, I hereunto subscribe my name this 15th day of January, 1929.
